UNITED STATES PATENT OFFICE.

JOHN STADLER, OF SHAWINIGAN FALLS, QUEBEC, CANADA.

SUSPENSION-EQUALIZING DEVICE FOR REVOLVING DRUMS.

1,351,497.

Specification of Letters Patent. Patented Aug. 31, 1920.

Application filed April 19, 1919. Serial No. 291,896.

To all whom it may concern:

Be it known that I, JOHN STADLER, a subject of the King of Great Britain, residing at Shawinigan Falls, Province of Quebec, Canada, have invented certain new and useful Improvements in Suspension-Equalizing Devices for Revolving Drums; and I do hereby declare that the following is a full, clear, and exact description of the invention, such as will enable others skilled in the art to which it appertains to make and use the same.

This invention relates to suspension equalizing devices for revolving drums, used mainly in connection with wood barking machines, and the principal object thereof provides for an arrangement of balancing levers in conjunction with revolving drums suspended from above by chains or other flexible mediums carried over wheels and having more than two suspending chains.

A further object of the invention is to provide an automatic equalizing device having means whereby drums of different length may be suspended and the load carried by the respective suspending chains proportioned as desired.

Another object of the invention is to overcome stresses due to eccentric location existing between the carrying rings and the consequent heavy stresses among the various suspending chains at every revolution of the drum.

A still further object of the invention provides U shaped pedestals for carrying the suspending chain wheel shafts, which U shaped pedestals assure a parallel location or movement of the shaft bearings thus avoiding undue friction and consequent loss of power and delay in operation.

With the above and other objects in view which will hereinafter appear as the description continues, the invention consists of the novel features of construction, combination and formation of parts as will be hereinafter more fully described and particularly pointed out in the appended claims.

In the accompanying drawings has been shown a simple and preferred form of the invention, it being, however, understood that

no limitation is necessarily made to the precise structural details herein exhibited, but the right is hereby reserved to any changes, alterations or modifications to which recourse may be had that come within the scope of the claims without departing from the spirit of the invention or sacrificing the efficiency of the same.

In the accompanying drawings:

Figure 1 is a top plan view of the suspension table and the equalizing mechanism;

Fig. 2 is a modified form of the equalizing mechanism and showing the application of the suspension mechanism to the drum; and,

Fig. 3 is a detail sectional view of one of the adjusting gears showing its mounting on the table.

Referring now more particularly to the accompanying drawings wherein like and corresponding parts are designated by similar reference characters throughout the several views—

In connection with the wood barking industry, perforated and solid drums as indicated by the numeral 1 in the drawings, are of considerable length and are required to run in places which make the application of carrying wheels and drive beneath them impossible, and mechanical suspension has been resorted to, with the mechanical equipment above, where it is easily accessible and if the drum is used for purposes that require liquids for the process, or for cleansing, the location of the machinery above the drums permits the proper care of same.

The supporting table 2, is provided with suitable mounting not illustrated and the bearing frames 3 at one side of the supporting table 2, are fixedly mounted thereon, being substantially of U-shape, the legs 4, being spaced apart and carry bearing standards 5.

Wheels 6 are mounted in the bearing standards 5 and each bearing frame 3 is so positioned with respect to the table 2, that the opening between the legs 4, registers with similar openings 7 in the table.

A similar plurality of bearing frames 8, 100

are mounted on the opposite side of table and in alinement with frames 3, but these frames 8, are adjustably mounted on the sub-bases 9, being movable in a horizontal direction and at right angles to the axis of the shafts 10, carrying the wheels 6.

A plurality of endless suspending chains 11, carrying the drum 1, pass over wheels 6 and through the openings 7. Bearing frames 10 3 are connected together in couples by the fixed beams 14, while the bearing frames 8, are connected together by the balancing beams 15. Rocker pins 16 connect the beams 14 and 15, and are mounted in bearings 16' fastened to the said beams 14 and 15.

The connection between the balancing beams 15 and the bearing frames 8, is effected by the positioning bars 17, having flat knife members 18 at each end and which 20 engage in suitable seats 19 in bearing frames 8 and the said balancing beams 15.

When the drum is of a dimension requiring the use of more than two chains, the division of the load and stress upon the 25 chains is difficult. Manual adjustments provided heretofore have permitted adjustment in installation, but as soon as the drums are put into operation elongation takes place on the chains, which is not uniform and the 30 bulk of the load will be carried by probably only two chains, causing excessive wear and consequent breakage.

Furthermore, on large drums it is not possible to assemble them at the factory and 35 machine the carrying rings all concentric on the completed drums; therefore, invariable eccentric location exists between the carrying rings of such a drum, which causes heavy stress among the suspending chains 40 at every revolution of the drum, which is overcome by my present device, due to the fact that the compensating of irregularities or eccentricity of the supporting rings or elongation of the suspending chains, is automatically done and thus the suspending 45 chains are always carrying their proportionate load.

In the present invention the balancing beams 15 act in conjunction with the revolving drum suspended from above by means of the chains 11 carried over the wheels 6, and any movement by the drum is therefore automatically compensated by the balancing beams 15.

50 The mounting illustrated in Fig. 3, shows the leg members 4 of the movable frames 8, formed with channels 20 which have bearings on the rails 21 of the sub-bases 9 and the gears are mounted on their shafts 10 and positioned directly above the openings 7 and in alinement therewith.

As will be clearly understood, the drum when it revolves on its shaft, is supported by the chains and every movement of the

latter is taken up by the said chains. Likewise adjustment may be made by regulating the positioning bars 17, so that an accurate adjustment is possible, balancing lever 15 always performing its function of equalizing the stress.

70 It is likewise obvious, that I may construct the positioning bars 17 in such manner that the flat knife members 18, may be adjusted longitudinally with respect to the seats 19 in the bearing frames 8 and the balancing beams 15, and for said purpose, I would provide thread connections on the bars 17 and the knife members, so that upon adjustment of the former the said knife members would be advanced or retracted, 80 serving to regulate the degree of swinging movement of the beams 15.

Having thus fully described my invention, what I claim as new and desire to secure by Letters Patent is:

85 1. The combination with a wood barking machine having a support, chains suspended from said support for supporting a revolving drum, of stationary and movable bearings mounted upon said support, sprocket 90 wheels journaled within said bearings over which pass said chains, an equalizing beam connecting each pair of movable bearings and said beams being pivotally supported to said stationary bearings.

95 2. The combination with a wood barking machine having a support, chains suspended therefrom and a drum carried by said chains, of stationary bearings mounted upon said support, movable bearings mounted upon said support, equalizing beams connecting said bearings, wheels journaled within said bearings, said chains adapted to pass over said wheels.

100 3. The combination with a wood barking machine having a supporting table, chains suspended therefrom and a drum carried by said chains, stationary bearings mounted upon and at one side of said table, slidable bearings mounted upon the opposite side of 110 said table, an equalizing bar connecting said slidable bearings, means for connecting said bar with said stationary bearings, wheels journaled within said bearings and said chains passing over said wheels.

115 4. A suspension device for revolving drums, comprising a supporting table, a plurality of slidable bearing frames mounted on said table, a plurality of oppositely disposed stationary bearing frames secured to 120 said table, wheels mounted in said frames, chains passing over said wheels and adapted for supporting a drum, means arranged between said frames for equalizing the stress encountered by the chains, and means for 125 adjusting certain of said frames with respect to the other frames.

5. The combination with a wood barking

machine having a supporting table, chains suspended therefrom and a drum carried by said chains, stationary bearings arranged upon one side of said table, slideable bearings mounted upon the opposite side of said table, a stationary bar connecting each pair of stationary bearings, an equalizing bar pivotally connected to said stationary bar,

an adjustable connection between the opposite ends of said equalizing bar and each 10 slideable bearing, wheels journaled within said bearings and said chains passing over said wheels.

In witness whereof I have hereunto set my hand.

JOHN STADLER.
